[57] CLAIM

The ornamental design for an ear protector, as shown and described.

DESCRIPTION

FIG. 1 is a right side elevational view of an ear protector showing my new design, the head shown in broken lines is for illustrative purposes only and forms no part of the claimed design;

FIG. 2 is a perspective view thereof;

FIG. 3 is a rear elevational view thereof;

FIG. 4 is a right side elevational view thereof, the left side being a mirror image;

FIG. 5 is a front elevational view thereof;

FIG. 6 is a top plan view thereof; and,

FIG. 7 is a bottom plan view thereof.
